UNITED STATES PATENT OFFICE.

JACOB I. BRORBY, OF SHENANDOAH, IOWA.

STREET-FLUSHING MACHINE.

1,019,126.

Specification of Letters Patent.

Patented Mar. 5, 1912.

Application filed March 25, 1911. Serial No. 616,805.

To all whom it may concern:

Be it known that I, JACOB I. BRORBY, a citizen of the United States, residing at Shenandoah, in the county of Page and State of Iowa, have invented new and useful Improvements in Street-Flushing Machines, of which the following is a specification.

The present invention relates to apparatus 10 designed chiefly for cleansing paved streets by flushing them with water, which is expelled from a tank under pressure, the pressure being created by compressing air and utilizing the pressure of the water when 15 charging the tank.

The invention provides means for automatically closing the outlet from the water compartment of the tank after the water has been nearly expelled therefrom, thereby preventing the escape of the compressed air.

A further purpose of the invention also resides in means for automatically closing the water compartment when nearly filled with water so as to prevent forcing the water 25 into the air compartment.

A further purpose of the invention is the provision of means whereby the pressure of the water may be utilized to charge the air compartment with air under pressure and 30 to locate a pressure regulator between the compressed air and water compartments so as to regulate the force of the water escaping at the outlets and to maintain such force uniform during the entire discharge of the 35 water.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a side view of the apparatus for flushing paved thoroughfares embodying the invention. Fig. 2 is a central longitudinal section of the tank and parts coöperating therewith.

Corresponding and like parts are referred to in the following description, and indicated in all the views of the drawings, by the same reference characters.

The tank is indicated at 1 and may be of any capacity and construction and is subdivided by means of a partition 2 to provide 55 two compartments 3 and 4, the latter containing the water for flushing the street and

the former containing the air under pressure to be utilized for expelling the water from the compartment 4. A pipe 5 connects with the bottom of the compartment 4 and is 60 adapted to be utilized for filling the water compartment and for discharging the water therefrom. A check valve 6 is located in the length of the pipe 5 to prevent escape of the water from the pipe 5 after the same 65 has been disconnected from the hydrant or other means for supplying water to the tank. Pipes, not shown, may be connected to the pipe 5 for discharging the water at the desired point or points. A fitting 7 is located at the juncture of the pipe 5 with the

70 tank and is provided with a seat 8 surrounding the outlet, said seat being adapted to be closed by means of a float valve 9. A short pipe 10 connects with the upper part of the 75 tank, a fitting 11 similar to the fitting 7 being located at the juncture of the pipe 10 with the tank and said fitting having a seat 12 against which the float valve 9 is adapted to close. A pipe 13 connects the upper end of the pipe 10 with the air compartment of the tank, said pipe 13 having a vertical branch

75 which extends through the air compartment and terminates a short distance below the bottom thereof. A trap 15 fitted to the 80 bottom of the air compartment receives the lower end of the vertical pipe 14, said trap having its lower end closed by means of a cap, which is removable to admit of drawing off any water or other matter that may 85 accumulate in the trap. T fittings 16 are located at the junctures of the vertical branches with the horizontal branches of the pipes 5 and 13. A rod 17 passes through the T fittings 16 and through the water compartment 4 and the vertical branches connecting the pipes 5 and 13 with the air compartment. The float valve 9 is mounted 90 upon the rod 17 and is directed in its movements thereby. The rod 17 passes centrally 95 through the valve seats 8 and 12 and insures a square seating of the float valve. When the water is expelled from the compartment 4 and just prior to the breaking of the seal the valve 9 closes upon the seat 8, thereby 100 preventing escape of the compressed air. When the water compartment is nearly filled with water during the charging thereof the float valve 9 closes against the seat 12, thereby preventing any water passing 105 from the compartment 4 through the pipes 10, 13 and 14 into the air compartment

3. It will thus be understood that the float valve is automatic in action so as to prevent flooding of the air compartment or escape of the compressed air when the water compartment 4 is nearly empty.

A valve 18 is located in the length of the pipe 13 and a branch 19 having a valve 19 is also connected with the pipe 13. The valve 18 and branch 19 are connected with 10 the pipe 13 intermediate the ends of the looped pipe 20, which latter constitutes in effect a bypass around the valve 18 and valved branch 19. A pressure regulator 21 is located in the length of the pipe 20 to 15 regulate the pressure of the water in its passage from the air compartment 3 into the water compartment 4, whereby the water discharged at the outlets may exert a practically uniform pressure throughout its dis- 20 charge from the compartment 4. A valve 22 is located in the length of the pipe 20 to control the flow of air therethrough. Pressure gages 23 and 24 are interposed in the length of the pipe 20 to indicate the 25 pressure of the air upon opposite sides of the pressure regulator 21 so that the pressure of the air contained in the compartment 3 and the pressure of the air in the upper portion of the compartment 4 may be 30 determined, thereby enabling the pressure regulator 21 to be properly set.

When it is required to charge the compartment 3 with air under pressure the valves 19 and 22 are closed and the valve 35 18 opened and water is admitted into the compartment 4 through the pipe 5 from a hydrant or other fixture connected with the source of water supply. As the compartment 4 fills with water the air expelled 40 therefrom passes into the compartment 3 through the pipes 10, 13 and 14. When the compartment 4 is nearly or quite filled the float valve 9 closes against the seat 12, thereby cutting off communication between 45 the two compartments so as to prevent any water passing from the compartment 4 into the compartment 3. The valve 18 is now closed and the valve 19 opened, thereby admitting air into the compartment 4 from 50 which the water is allowed to pass off. After the compartment 4 has been emptied the valve 19 is again closed and the valve 18 opened and the compartment 4 permitted to again fill with water, the air expelled 55 therefrom passing into the air compartment 3. This operation is repeated until the pressure in the gage 23 corresponds with the water pressure. After the compartment 3 has been charged with air under pressure 60 corresponding with the pressure of the water the compartment 4 is filled, after which the valves 18 and 19 are closed and the valve 22 opened, thereby permitting air to pass from the compartment 3 65 through the pipe 14, bypass 20 and pipes

13 and 10 into the water compartment 4. The pressure gages 23 and 24 will indicate the differences between the air pressures in the compartments 3 and 4, the pressure regulator 21 being set so that the air pressure 70 exerted upon the water in the compartment 4 will correspond to that required to force the water from the compartment 4 through the discharge outlets. When the compartment 4 is nearly or quite empty the valve 9 will 75 close upon the seat 8, thereby shutting off the outflow and preventing the escape of the compressed air. The compartment 4 is now recharged, the air expelled therefrom passing into the compartment 3 in the 80 manner hereinbefore stated. By having the pipe 14 extend into the lower portion of the compartment 3 or preferably into the trap 15 any water finding its way into the compartment 3 is forced therefrom by the pressure of the air through the pipe 14 and 85 pipes 13 and 10 into the water compartment 4, thereby keeping the compartment 3 practically free from any water. The rod 17 in addition to forming a guide for the float 90 valve 9 also serves to secure the vertical branches of the pipes to the tank.

From the foregoing description, taken in connection with the accompanying drawings, the advantages of the construction and of the method of operation will be readily apparent to those skilled in the art to which the invention appertains, and while I have described the principle of operation of the invention, together with the device which 100 I now consider to be the embodiment thereof, I desire to have it understood that the device shown is merely illustrative, and that such changes may be made when desired as are within the scope of the claims appended 105 hereto.

Having thus described the invention what is claimed as new, is:—

1. In a street flushing apparatus, the combination of a tank embodying water and air 110 compartments, the water compartment having upper and lower openings, pipes having vertical branches connected with the tank in line with the said openings, a rod passing through the tank and through the openings 115 thereof and the said vertical branches and serving to connect the latter to the tank, and a float mounted upon said rod and adapted to automatically close the openings and controlled in its movements by the 120 change of level of the water in the tank.

2. In a street flushing apparatus, the combination of air and water compartments, a supply and discharge pipe connected with the bottom of the water compartment, an 125 air pipe having connection with the top of the water compartment in vertical line with the point of connection of said supply and discharge pipe therewith, and having a vertical branch extending through the air com- 130

partment and the bottom thereof, a trap fitted to the bottom of the air compartment and receiving the lower end of the said vertical branch, a pipe looped into the air pipe, 5 a pressure regulator, pressure gages and a valve located in the length of the looped pipe, a valve and a valved branch connected with the air pipe intermediate the two ends of the said looped pipe, a float valve for 10 closing the air pipe and the said supply and

discharge pipe and adapted to be actuated by the change of level of the water in the water compartment, and a guide for directing the float valve in its movements.

In testimony whereof I affix my signature in presence of two witnesses.

JACOB I. BRORBY.
